UNITED STATES PATENT OFFICE

CARL MARTIN CLEMENTSON AND SVEN OLA HEINRICH CLEMENTSON, OF MALMO,
SWEDEN

INTERNAL-COMBUSTION ENGINE

Application filed August 24, 1927, Serial No. 215,202, and in Sweden September 23, 1924.

Our invention relates to internal combustion engines and more particularly to an improved valve structure for such engines.

The object of the invention is to provide a 5 rotary valve structure designed for continuous rotation during the run of the engine to which the said structure is applied and to operate with a very low speed of rotation and with the expenditure of a minimum amount 10 of power; such structure being formed with large ports for the admission of the fuel mixture and for the exhaust.

Further objects and advantages of the invention will be explained in the course of the 15 following detailed description; reference being made to the accompanying drawing in which Fig. 1 is a vertical section through the upper part of an engine cylinder, equipped with the valve structure according to the invention, along the axis of rotation of the latter, while Fig. 2 is a cross section along the broken section line $x-x$ $y-y$ in Fig. 1.

In the drawing, numeral 1 indicates the casing of the engine, which casing may contain either a single cylinder or a plurality of integral cylinders, and 2 indicates the cylinder head. The latter comprises an inner wall 3 surrounded by a cooling water jacket 16 which constitutes a continuation of the main 20 water jacket hereinafter referred to; and said wall is provided with ports 19 forming fuel admission openings to the cylinder, and with a hollow rotary valve body in the form of a sleeve 4, which is provided with at least 25 four pairs of diametrically opposite inlet ports 5, and with at least four pairs of diametrically opposite exhaust ports 6, the latter ports being axially displaced in relation to the inlet ports. Within the sleeve 4 is arranged a non-rotating core member 7, which is hollow and provided with ports 8 and 9 equal in number with and of a similar arrangement to the inlet ports 5 and the exhaust ports 6 respectively. The said core 30 member 7 is divided by means of a partition

wall 10 into two compartments, of which the compartment 11 on the one side of said wall is intended for the fuel admission and the other compartment 12 on the other side of the wall for the exhaust.

Rotation is imparted to the valve sleeve 4 by means of a gear 13 affixed to a central stud on one end wall of said sleeve, which wall closes the outer end of the compartment 11, said stud extending outside of the wall 3 of the cylinder head as shown in Fig. 1. The gear 13 is intended to be in mesh with a worm driven from the main shaft of the engine (not shown).

14 represents a threaded boss for affixing a suitable pipe leading to the carburetor, and 15 represents a similar boss in communication with the compartment 12 and intended for connection of an exhaust pipe. The casting 1 encloses a water space 16 around the cylinder 17, the piston of which is indicated by the numeral 18.

The operation of the valve structure is as follows:

When the rotary valve sleeve 4 rotates, the inlet ports 5 in the same are brought into register with the inlet ports 8 in the hollow core member 7, and since the ports 19 in the wall 3 of the cylinder head are arranged in alignment with the ports 5 the fuel mixture may 70 freely pass from the carburetor and the boss 14 into the cylinder 17 at the fuel admission stroke. When the exhaust ports 6 at the other side of the wall 10 in the rotary valve sleeve 4 in the same manner are brought into register with the exhaust ports 9 of the hollow core member 7, it will also be apparent that a communication will be established between the cylinder 17 and the exhaust pipe during the exhaust stroke. Since there are not less 75 than four ports on each side, and since these ports are equally spaced on the circumference of the valve structure, it is obvious that the valve sleeve may rotate with a very low speed or, in the case shown a speed amounting 80

to only one-eighth that of the crank shaft, and it will be obvious that the driving means connecting the gear 13 with the crank shaft must be constructed so that the opening and closing of the inlet and exhaust ports are correctly timed in relation to the position of the pistons in their cylinders.

It will be obvious that the valve structure according to the invention will provide for a plurality of large and free passages both for admitting the fuel charge and for expelling the exhaust gases, and the tightening between the open and the closed position is very effective.

What we claim and desire to secure by Letters Patent is:—

1. In an internal combustion engine, a valve structure for a single cylinder comprising, in combination, a head individual exclusively to the cylinder and provided with a cylindrical seat, a horizontal valve sleeve rotatably mounted in said seat and having one end closed, a hollow stationary core member secured to the cylinder head and fitting conformably within said sleeve, a partition wall within the core member dividing the same into two compartments, one of which is closed at its outer end by the closed end of the sleeve, while the other is in communication at its outer end with the exhaust pipe, and means disposed laterally with relation to the cylinder head for introducing fuel thereinto; said core member and said seat each having a large number of ports therein arranged in alignment, and said sleeve having the same number of ports so arranged as to be brought into register with the first-mentioned ports a large number of times during each rotation of the sleeve, the various ports being divided into two groups arranged one at each side of the partition wall, each series conjointly forming a single port of large total area.

2. In an internal combustion engine, a valve structure comprising, in combination, a cylinder head provided with a cylindrical seat, a valve sleeve rotatably mounted in said seat, a hollow stationary core member secured to the cylinder head and fitting conformably within said sleeve, a partition wall within the core member dividing the same into two compartments, one of which is in communication with the exhaust pipe, and means for introducing fuel into the cylinder head; said core member and said seat each having a large number of port openings therein at each side of the partition wall, each such number or set of openings conjointly forming a single port of large total area, the corresponding openings in the core member and seat aligning with each other; and said sleeve also having a large number of port openings at each side of the partition wall, each number or set of sleeve openings likewise conjointly forming a single port of large total area and adapted to be brought periodically into

register simultaneously with the corresponding first-named set a number of times during each rotation of the sleeve, whereby rotation of said sleeve through a small angle will effect a substantially-instantaneous opening or closing of a port unit.

3. An internal combustion engine, according to claim 2, in which the openings of the several sets of openings are arranged in diametrically-opposite pairs.

In testimony whereof we have affixed our signatures.

SVEN OLA HEINRICH CLEMENTSON.
CARL MARTIN CLEMENTSON.
